FASTENING-INSERTING MACHINE

John T. Lancaster, Newton, Mass., assignor to
 United Shoe Machinery Corporation, Borough
 of Flemington, N. J., a corporation of New
 Jersey

Application June 13, 1939, Serial No. 278,891

13 Claims. (Cl. 1—32)

This invention relates to machines by which fastenings are inserted to join work-pieces. It is more particularly concerned with apparatus of the character of that described and claimed in 5 Letters Patent of the United States No. 2,033,158, Standish, March 10, 1936, in which the reactive force produced by the insertion of the fastenings is utilized to apply clamping pressure to the work, to a degree in proportion to the resistance encountered by the fastenings. The invention 10 finds a desirable application in machines for attaching heels to shoes by inside-nailing.

In the machine of the above-mentioned patent, there is normally maintained automatically, 15 such a relation between the force required to drive the nails, or other attaching fastenings, through the heel-seat of a shoe into an applied heel, and the force necessary to retain the heel against displacement; that these are substantially equal and opposite, and the heads of the 20 nails will be uniformly seated in the insole of the shoe with the heel firmly attached. While this is ordinarily true, even when there are considerable changes in the character of the heels, conditions may enter which cause the ratio between 25 the forces to be disturbed. Under such circumstances, the nail-heads may be left projecting from the insole, because the drivers yield in a direction opposite to their inserting movement, 30 during the application of clamping pressure to the work. It is an object of my invention to ensure uniformity in the action of the machine, regardless of the character of the work.

To attain this object, I combine with a work- 35 support, for example the jack of a heel-attaching machine, work pressing mechanism, which may include a heel-abutment, and fastening mechanism, as a driver-plunger and its drivers reciprocating in the jack, together with primary 40 means for actuating the inserting mechanism and secondary actuating means for said inserting mechanism, the secondary means being made effective in the operation of the primary means. If the drivers yield oppositely to their fastening- 45 inserting movement under the influence of the primary means, the secondary means will produce relative movement between the jack or work-support and the drivers, to compensate for the yield. This secondary means is made 50 effective by the same reactive force which clamps the work for the inserting operation. In the specific embodiment of the invention herein disclosed, a reciprocating plunger is formed in sections, one of which carries the drivers while

the other is engaged by actuating means. The sections are connected by means movable in the operation of the machine for varying the relation between said sections, this means being shown as a nut connecting threaded portions of the plunger and rotated by movement of the primary actuating means and the work-clamping means together as a unit. Thus, when the drivers are depressed, a compensating effect is communicated through the actuating means to correspondingly elevate them and ensure a full sinking of the nail-heads.

In the accompanying drawings,

Fig. 1 is a front elevation of a heel-attaching machine, including one of the several possible 15 forms of my invention; and

Fig. 2 is a central, vertical, longitudinal section therethrough.

To state briefly the more essential features of 20 the machine in connection with which I have chosen to illustrate my invention, a frame 10 carries at its upper, front portion a work-supporting jack 12, provided with vertical passages in which are arranged to reciprocate drivers 14 for nails or other fastenings. These drivers rise 25 from a plunger 16, guided for vertical reciprocation in the frame and having at the bottom a rotatable roll 18, which is urged by a spring 20 into contact with an actuating cam 22. The cam is fast upon a short horizontal shaft 24, rotatable in a block 26 guided in the frame and held in a normally raised position by opposite springs 28. The cam-shaft is rotated through an Oldham-coupling 30 from a main shaft 32, and power is applied to such main shaft from a driven 35 pulley 34 through clutch mechanism 36. Depending from the block 26 is a tubular piston 38, operating in a liquid-containing cylinder 40. The cylinder furnishes the lower portion of a slide having side-rods 42, 42, guided in the frame 40 and joined at their upper extremities by a yoke 44. The yoke carries an abutment 46, arranged for engagement with a heel H to be clamped upon the heel-seat of a jacked shoe S. A spring 48 holds this compound slide normally elevated, with the abutment raised from the jack, while 45 said slide may be lowered by a treadle 50 and connections at 52 to cause the abutment to apply preliminary pressure to the jacked work. This having been accomplished, a connection to the treadle at 54 trips the clutch to produce a power 50 cycle of the machine, starting the rotation of the cam 22. The contour of this cam causes it to at once permit a valve 56 to close the end of 55

the piston 38, locking together the piston and the cylinder 40 through the contained body of non-compressible liquid so they will move as a unit. As is fully explained in the previously mentioned Standish patent, the continued rotation of the cam raises the plunger 16, so the drivers 14 insert the nails, which they bear upon their upper ends, through the heel-seat of the shoe into the heel. Any resistance encountered in the elevation of the drivers produces a reaction resisting the turning of the cam, and thus, in its contact with the roll 18, exerts a force upon the block 26 and the locked piston and cylinder, together with the other parts of the slide, so the abutment 46 places final clamping pressure upon the work to resist the insertion of the nails. Since the reaction is opposite and approximately equal to the resistance which creates it, the clamping pressure is generally that required to hold the work firmly against displacement, without danger of crushing the heel or wrinkling its covering.

In an apparatus such as that above outlined, there may be characteristics of the material operated upon, which will so disturb the ratio between action and reaction that the clamping force placed upon the heel will be excessive. This would follow were the heel-material to be rather compressible, and yet offer considerable resistance to its penetration by the nails. Or, the heel-material may lack uniformity, the portion which the nails enter being harder than the opposite side against which the abutment bears. When such conditions obtain, as the work is compressed, the abutment 46 moves down under the action of the rotating cam 22 upon the block 26 and the intermediate connections to the abutment, more rapidly than said cam can elevate the plunger 16 and its drivers 14. As a result of this, after the cam had completed its rotation and had permitted the retraction of the plunger by its spring 20, the upper ends of the drivers would not have reached the points for which they were set, and the heads of the nails would be left projecting from the insole of the shoe. This failure to sink the nail-heads, I correct in the following manner. The plunger is formed in sections, there being the upper portion, already designated as 16, upon which the drivers are mounted, and a lower portion 60. The inner ends of these sections are spaced from each other at 62, and there extend into this space from the sections projections 64, 64, on which right and left screw-threads are respectively formed. Encircling these projections is a correspondingly threaded right and left nut 66, having elongated gear-teeth upon its exterior. Meshing with these teeth, and reciprocable in guides 68, 68 upon the frame 10, is a rack 70. Into one end of the rack is threaded a screw 72 surrounded by an eccentric bushing 74, which may be secured in different angular positions by the screw. A link 78 is pivoted about the bushing, and at its outer extremity is joined the vertically-extending arm 80 of a bell-crank-lever fulcrumed upon the frame, the horizontal arm 82 of said lever being connected by a link 84 to the forward end of the cam-shaft 24.

The effect of the connections between the cam-shaft and the driver-plunger is as follows. Assume that during the power-cycle of the machine the character of the work operated upon causes the cam 22, furnishing the primary actuating means for the drivers 14 and acting against the plunger-roll 18, to materially lower the bearing

block 26 and the connected abutment 46. As this compresses the heel H, the uncontrolled effect would be to allow the spring 20 to urge the driver-plunger down as far as this descent of the cam permitted as a result of this bodily movement of the cam, the drivers would have been raised to a less extent than that for which they are set, and the heads of the nails would not reach the insole. But, upon any such downward travel of the cam, its shaft 24 imparts its movement of translation to the link 84. The bell-crank-lever 80, 82 is thereby turned clockwise (Fig. 1) thrusting the rack 70 to the right, and so rotating the nut 42 as to separate the threaded plunger-projections 64, 64 and elevate the upper section 16 of the plunger upon the lower section 60. The ratio between the lever-arms 82 and 80 and the pitch of the threads upon the projections 64 are so proportioned that the distance through which the drivers are elevated by this secondary actuating means, will equal that through which the cam-shaft is lowered because of the compression of the work. Consequently, the nail-carrying ends of the drivers will rise to the desired points, and the nail-heads will be fully embedded in the insole. The normal positions of the drivers as a group may be determined conveniently by rotating the bushing 74 and clamping it by the screw 72. This alters the initial position of the rack 70 and the degree of separation of the plunger-projections 64 to raise or lower the drivers.

Having described my invention, what I claim as new and desire to secure by Letters Patent of the United States is:

1. The combination with a work-support, of work-pressing mechanism and fastening-inserting mechanism cooperating with the support, primary means for actuating the inserting means, and secondary means made effective in the operation of the primary means for actuating said inserting mechanism.

2. The combination with a work-support, of a work-pressing member co-operating therewith, drivers movable to insert fastenings in the supported work, said drivers being capable of yielding in a direction opposite to their inserting movement, and means operating during the yield of the drivers for producing relative movement between the work-support and said drivers to compensate for their yield.

3. In a heel-attaching machine, the combination with a work-support, of a work-pressing member co-operating therewith, fastening-inserting drivers movable toward the work-pressing member to insert fastenings in supported work, primary means for imparting to the drivers their inserting movement, and secondary means for moving the drivers in the same direction as the primary means, both the primary and secondary means operating under the power of the machine.

4. The combination with a work-support, of means for pressing the work upon the support, drivers reciprocating in the support and being depressed from its work-engaging surface, means for elevating the drivers to insert fastenings in the work, and means operating as a result of the depression of the drivers for elevating said drivers to compensate for their depression.

5. The combination with a work-support, of fastening drivers movable therein, pressure means for engagement with the supported work, means for transmitting to the pressure means the reaction of the drivers in the insertion of the fasten-

ings, and means made effective by the reactive force for moving the drivers toward the work.

6. The combination with a work-support, of fastening-drivers movable therein, a movable actuating member for the drivers, a work-pressing member co-operating with the support, means for connecting the actuating member and the work-pressing member to move together as a unit, and means for communicating the movement of 10 the connected members to the drivers.

7. In a heel-attaching machine, a jack, drivers reciprocating in the jack, a heel-abutment movable toward and from the jack, means made effective by the elevation of the drivers for forcing 15 the abutment into heel-clamping relation, and means made effective by movement of the abutment for elevating the drivers.

8. In a heel-attaching machine, a work support, a reciprocatory plunger formed in sections, 20 nail-drivers carried by one section, actuating means for the other section, and means connecting the sections and being movable in the operation of the machine for varying the relation between the sections.

25 9. In a heel-attaching machine, a frame, a jack mounted upon the frame and provided with nail-receiving passages, a plunger reciprocating in the frame and having drivers operating in the jack-passages, actuating means for elevating the plunger and being mounted to yield upon the 30 frame, and means for elevating the plunger as a result of said yield.

10. In a heel-attaching machine, a frame, a jack mounted upon the frame and provided with 35 nail-receiving passages, a plunger reciprocating in the frame and having drivers operating in the jack-passages, actuating means for elevating the

plunger, a heel-abutment co-operating with the jack, means for connecting the actuating means and the abutment to move together, and means whereby such joint movement elevates the drivers.

11. In a heel-attaching machine, a frame, a jack mounted upon the frame and provided with nail-receiving passages, a plunger reciprocating in the frame and being formed in sections, said sections having oppositely threaded portions with 10 a surrounding nut, nail-drivers carried by one section and operating in the jack-passages, actuating means for the other section, and means for rotating the nut.

12. In a heel-attaching machine, a frame, a jack mounted upon the frame and provided with nail-receiving passages, a plunger reciprocating in the frame and being formed in sections, said sections having oppositely threaded portions with 15 a surrounding nut, a heel-abutment co-operating with the jack, means for transmitting movement of the actuating means to the heel-abutment, and means whereby movement of the abutment rotates the nut.

13. In a heel-attaching machine, a frame, a jack mounted upon the frame and provided with nail-receiving passages, a plunger reciprocating in the frame and being formed in sections, said sections having oppositely threaded portions with 20 a surrounding nut, a heel-abutment co-operating with the jack, means for transmitting movement of the actuating means to the heel-abutment, a lever fulcrumed upon the frame and connected to the actuating means, and gearing by which the 25 lever rotates the nut.

JOHN T. LANCASTER.
